CLAIM

The ornamental design for a vehicle hood vent, as shown and described.

DESCRIPTION

FIG. 1 is a front elevational view of a first embodiment of a vehicle hood vent, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a top, front and left side perspective view thereof;

FIG. 7 is a top, rear and left side perspective view thereof;

FIG. 8 is a front elevational view of a second embodiment of a vehicle hood vent, showing our new design;

FIG. 9 is a rear elevational view thereof;

FIG. 10 is a left side elevational view thereof;

FIG. 11 is a right side elevational view thereof;

FIG. 12 is a top plan view thereof;

FIG. 13 is a top, front and left side perspective view thereof; and,

FIG. 14 is a top, rear and left side perspective view thereof. The broken lines and lightened elements illustrate portions of the vehicle hood vent which forms no part of the claimed design.
